UNITED STATES PATENT OFFICE.

CORNELL FLAGSTAD, OF MINNEAPOLIS, MINNESOTA, ASSIGNOR OF ONE-FOURTH TO IVAR SIVERTSEN, ONE-FOURTH TO JOHN P. JACOBSEN, AND ONE-FOURTH TO OSCAR FLAGSTAD.

NAILHEAD-SPACING DEVICE.

Application filed August 25, 1923. Serial No. 659,362.

To all whom it may concern:

Be it known that I, CORNELL FLAGSTAD, a citizen of the United States, residing at Minneapolis, in the county of Hennepin and State 5 of Minnesota, have invented certain new and useful Improvements in Nailhead-Spacing Devices, of which the following is a specification.

This invention relates to nail head spacing devices and the main object is to provide 10 a simple, efficient and practical means for spacing a nail head away from the object into which it is driven, so that it may be easily accessible for being pulled out by a 15 claw hammer or other instrument, when so desired. It is well known, especially in the crate and box manufacturing field, that after a container of that class has been filled and shipped to its destination, it 20 must be and usually is so ripped and split to pieces, when removing the contents, that it is thoroughly wrecked, rendering it unfit for future use as such. In order to prevent this useless waste of good shipping containers, and also to satisfy a similar want in 25 many other places where it is known that a nail is to be pulled after it has been driven home, I provide a novel device, the preferred construction and many modifications of 30 which are shown in the accompanying drawing, in which:

Fig. 1 is a sectional perspective view of two pieces nailed together with a device embodying the invention.

Fig. 2 is a perspective view of the metallic elements shown in Fig. 1, but in spaced relation to each other.

Fig. 3 is a modification of the spacing elements shown in Fig. 2.

Fig. 4 is a bottom view of a device embodying a further modification over Fig. 2.

Fig. 5 is an enlarged detail section on the line 5-5 in Fig. 4.

Figs. 6, 7, 8, 9, 10, and 11 are all additional modifications of the device.

Fig. 12 is a detail perspective showing several of the modifications incorporated in a single device.

Referring to the drawing more particularly and by reference characters, A designates a strip of wood (or other material) 50 which is to be securely nailed to a larger or main piece B by a nail C. Instead of simply driving the nail through both pieces in

the usual manner, however, I provide a spacing device D, and in some instances a small plate E, through which the nail is first inserted, which device prevents the nail from being driven completely into the wood, and keeps it with its head far enough above the 60 wood so that a hammer claw or other similar tool may engage the device and pull it together with the nail upward, when it is desired to extract the nail.

The device is preferably made from a short rectangular strip of sheet metal and is substantially trilaterally formed, as shown, one face having a perforation F, to receive the nail, and the opposite edges being slightly open so that the nail can pass therebetween also. In Fig. 3 the spacer D² is shown to have rounded lower edges 14. In Figs. 4 and 5 the spacer D³ is provided at its lower edges with vertical tapered flutes or 70 grooves 15 which permit said edges to be closed together about the nail. These flutes may be large enough so that the nail will not be clamped thereby when the adjacent edges are forced together, if so desired, although the drawing indicates that the nail may be 75 so clamped. The sides of the spacer in these figures are also provided with punched out lips 16, to insure a more positive engagement by the hammer claws when the nail is to be extracted. The spacer D⁴ shown in Figs. 6 80 and 7 is provided, at its open edges, with small integral flanges 17, which prevent it from being driven into the wood when no plate E is used, or said flanges may engage 85 the plate E when the spacer is inverted, as shown in Fig. 7. The spacer D⁵, illustrated 90 in Fig. 8, is similar to the spacer D, but its ends are inwardly slanted at an angle substantially the same as the angle formed by the two side portions of the device, thus allowing the hammer claws to engage the ends 95 as well as the sides of the member. The modifications shown in Fig. 9 includes a spacer D similar to the one shown in Figs. 1 100 and 2, but as used with a plane plate or washer E² and with a regular box nail C². The spacer D⁶ shown in Fig. 10 is similar to the spacer D except that the lower corners have been cut away to allow for end engagement 105 of hammer claws as indicated above in connection with Fig. 8. The spacer D⁷ shown in Fig. 11, illustrates how it may be formed in the shape of a closed horseshoe, with sub-

stantially the same effect as when triangularly formed. The spacer device D^s shown in Fig. 12 incorporates the features 15—16, and 17 and E, shown in Figs. 4—5, 6, and 7, respectively.

The plate or washer E may be of any suitable shape, and may be secured on the wood, as shown in Fig. 1, or may be free, as indicated in Figs. 3, 7, 9 and 12. When a spacer 10 such as shown in Fig. 3 is used it is desirable to form the washer with a concave central portion 18 about the nail aperture so as to bring the curved spacer edges 14 close down and clamp them against the nail shank when 15 the latter is driven into place. It is also found desirable, especially when the plate E is to be fixed on the nailing strip A, to first drill a hole 19 into that strip to save driving the nail through that piece. In box making 20 and similar structures it may also be found desirable to provide the nailing strip A with a wide channel formed between projecting ribs 20, or similar guards, so as to give protection to the projecting spacers and nail 25 heads against lateral knocks or blows from obstacles coming in contact therewith.

It is understood that further modifications may be made in addition to those herein set forth, provided, however, that such modifications come within the spirit and scope 30 of the appended claims.

Having now therefore fully shown and described my invention, what I claim is:

1. A perforated spacing device having integral converging side portions spaced at 35 their near edges to receive a nail inserted in

the perforation so that said edges will be forced toward the nail when the latter is driven with its head down against the spacer.

2. A device having a perforation adapted 40 to receive a nail and space its head from the object into which it is driven, said device having converging side portions adapted to be bent inwardly against the nail when the device is clamped between the nail head and 45 said object.

3. A device of the character described consisting of a perforated piece having converging sides, and oppositely arranged lips 50 formed integral with and punched outwardly from said converging sides.

4. A perforated spacer of the character described, having converging sides adapted to have their free edges close toward each other by compressing the spacer vertically. 55

5. A perforated spacer of the character described, having converging side portions adapted to have their near edges close toward each other by compressing the spacer vertically, said edges having outwardly extending integrally formed flanges, as and for 60 the purpose set forth.

6. A perforated spacer of the character described, consisting of a member having converging side portions, the near ends of 65 which are free and slightly spaced from each other, and a perforated plate arranged under the spacer, said plate contacting with the free ends of the side portions.

In testimony whereof I affix my signature.

CORNELL FLAGSTAD.
